UNITED STATES PATENT OFFICE.

OTTO PETERMANN, OF GROTON, NEW YORK, ASSIGNOR TO CORONA TYPEWRITER COMPANY, INC., A CORPORATION OF NEW YORK.

TYPE-WRITING MACHINE.

1,194,420.

Specification of Letters Patent. Patented Aug. 15, 1916.

Application filed July 16, 1914. Serial No. 851,334.

To all whom it may concern:

Be it known that I, OTTO PETERMANN, a citizen of the United States, and a resident of Groton, county of Tompkins, and State of New York, have invented certain new and useful Improvements in Type-Writing Machines, of which the following is a full, clear, and exact description.

This invention relates more particularly 10 to a dead key action for typewriting machines for printing accents or for under-scoring purposes.

In visible typewriting machines where one or more dead or accent keys are employed, it is necessary that the construction be such that the ribbon vibrator will be moved to cover and uncover the printing point without tripping the escapement so that no letter feed movement is given to 20 the carriage during the actuation of said accent key or keys. In the particular type of machine shown in the drawings, which is of a visible foldable character wherein the carriage is adapted to be moved forward into substantially overchanging relation to the keys or the type-bars and wherein in a special form of escapement mechanism and ribbon vibrating mechanism is ordinarily employed and wherein both escapement 25 mechanism and ribbon vibrating mechanism are operated through the same element forming a connection with the universal bar, certain problems exist because of the fact that the ribbon should always be moved 30 to the same height and the same element that operates the ribbon vibrator should be moved in such a way that it will not trip the escapement. It is desirable too that the construction be such that it will permit a bichrome 35 ribbon to be employed and the ribbon exactly positioned with respect to the printing point to remove all liability to "bleeding". Another feature to be considered is means whereby accent or underscoring type, 40 owing to their small character, may be controlled in such a way that they will not be forced through the paper in printing and thereby injure the surface of the platen.

One of the principal objects of the invention 50 is to overcome the objections referred to and to meet the requirements specified, and to provide simple means whereby any one of a series of keys may be converted into a dead, silent or accent key, and the said key 55 made to operate a ribbon vibrator to move

the ribbon to and from the printing point a distance corresponding to that obtained by the ordinary key and at the same time prevent the tripping of the escapement so that the carriage will not be moved by its 60 letter-spacing mechanism.

Another object of the invention is to provide a simple and efficient attachment which may be arranged to form a stop or bumper bar effect for each key-operated lever, and to provide simple means whereby all of the 65 keys may have substantially the same extent of movement.

Other objects of the invention are to provide simple and efficient means whereby very 70 little change is required in typewriting machines of the visible, portable type to adapt any one of the keys to be made a dead or silent key; and to provide simple and efficient means whereby a single rocking frame 75 may be operated by all of the key-levers and with some of the key-levers given a greater movement than by others to adapt both the escapement and ribbon vibrating mechanisms to be operated by certain of the keys 80 and only the ribbon mechanism to be operated by one or more other keys.

A further object of the invention is to provide simple and efficient means forming a dead key action which is particularly 85 adapted for typewriting machines in which the carriage and the keys are brought into close relation with respect to each other in order that the machine may be made more compact when not in use than when in its 90 normal working condition.

With these and other objects in view, the invention will be hereinafter more particularly described with reference to the accompanying drawings, which form a part of this 95 application, and will then be pointed out in the claims at the end of the description.

In the drawings, Figure 1 is a longitudinal section, partly in elevation, of one form of machine embodying my invention. Fig. 2 is a fragmentary front elevation of the upper part of the machine. Fig. 3 is an inverted plan of a part of the ribbon vibrating mechanism detached from the machine. Fig. 4 is a detail plan view of the ribbon 100 vibrating mechanism removed from the machine showing a special form of actuating means. Fig. 5 is a view similar to Fig. 4 except that the vibrator is shown as having been moved to force the ribbon over the 110

printing point. Fig. 6 is an enlarged fragmentary transverse section, partly in elevation, of the ribbon vibrating mechanism. Fig. 7 is a detail plan view of the ribbon vibrator actuating means removed from the machine. Fig. 8 is a fragmentary front elevation, partly in section, of the vibrating mechanism. Fig. 9 is an elevation of the dead key attachment showing a part of the key-lever comb or guide plate to which said attachment is applied. Fig. 10 is a detail perspective view of the dead key attachment or device for engagement by any one of the key-levers to which it is applied; and Fig. 11 is a vertical section taken on the line XI—XI of Fig. 9.

While the invention is shown as applied to a typewriting machine such as disclosed in the reissue patent to Frank S. Rose, No. 20 13,934, dated June 22, 1915, wherein the carriage is mounted upon a foldable support in order that the carriage may be moved forward so as to substantially overhang the keys and in which the mechanism of the 25 Rose type of machine has been modified and such modifications and improvements embodied in different applications filed by me, it will be understood that the invention or certain parts thereof may be applied to typewriting machines of various kinds.

The frame 10 may be of any suitable construction and may comprise a back plate 11 and side plates 12. Extending transversely between the side plates 12 are rods 13, on 30 each of which is suspended a plurality of key-levers 14 so as to provide a series of banks of such key-levers in the usual way, one or more of said levers, as 14^a, being an accent or dead key-operated lever. Each 35 key-lever may be held in its normal position by a spring 15, one end of which is fastened to the key-lever and the other end to a transversely extending bar 16. At the inner end of each key-lever is an upwardly projecting 40 part 17 which is connected by a link 18 or otherwise to one of the type-bars 18^a so that on depression of any one of the key-levers the inner end of the key-lever may be forced upward so as to move the type 45 on the type-bar upward and rearward for printing purposes. Each ordinary key-lever may have a tongue or finger 19 which when forced upward is adapted to engage the lower edge of a universal bar 20, and each 50 dead key-lever may have its tongue or finger bent downwardly, as at 19^a, in order to engage the universal bar 20 later than the tongues 19 and thereby impart less movement to said bar. This universal bar 55 20 is provided with integral arms 21, the upper ends of which are pivoted, at 22, to the arms 23 of bell-crank levers 24. There are two bell-crank levers 24, one at each side of the machine, and said bell-crank levers are pivoted, at 25, to a part held to the machine

frame and may have an end 26 which is adapted to engage vertical slots 27 in the rocker arms 28. The arms 28 are connected together at their upper ends by an integral bar 29 so as to form an inverted substantially U-shaped frame, the lower ends of which are pivoted to a transversely extending rod 30. This rod 30 is pivoted to one or more arms 31 forming a part of a suitable platen shift mechanism, and said rod 35 30 is connected to slides, not shown, which are held to arms or bars forming a part of a foldable support 31^a. These arms or bars of the foldable support are pivoted together, at 32, and at their inner ends two of said bars are rigidly connected together by a carriage bed 33. On the bed 33 is a carriage 34 having a platen 34^a and a rack 35 which is adapted to be engaged by the dogs 36 and 40 37, the said dogs being mounted on a carrier 38. Suitable tension mechanism, as a spring drum 38^a, is provided whereby the carriage may be forced along its bed when the escapement is tripped by the rocking of the frame 28, the latter causing the engagement of a tappet 39 forming a part of the transversely extending bar 29 with the dog carrier 38. The carriage with the parts mounted on the carriage bed and the foldable part of the support are adapted to be moved forward over the keys. The parts as thus described, except as to the differently positioned tongues 19 and 19^a, are not claimed herein and such parts may be of the usual or of any preferred construction.

In order to give one or more of the keys or key-operated levers a bumper effect and prevent all liability of moving the rocking frame 28 far enough to trip the escapement, I provide one or more devices 40 which are attached to the machine in such a way as to form a positive stop for the key-lever with which it cooperates. Each key-lever at its inner end is provided with a part 41 which normally moves in a slot 42 of a comb or guide plate 43, there being a slot for each key-lever. The comb plate 43, Figs. 1, 9; 10 and 11, extends transversely of the machine and is supported at its opposite ends on brackets 44 or which may be otherwise secured to the machine frame. The body 45 of the device 40 is also provided with a slot 46 which is somewhat wider than the slots 42 of the comb or guide plate 43 and through which slot passes the end 41 of the key-lever which is to become a dead or silent key. The plate-like body 45 of the device or attachment 40 is provided at the upper portion thereof with a lip or stop portion 47 which projects inward within one of the slots 42 so as to shorten the length thereof and serve as a positive stop for the key-lever whose end 41 is adapted to be engaged by the stop 47. This stop is of such length that it will have a bumper effect and limit the extent of move- 130

ment of the rocking frame 28 and the key-lever with which it coöperates without liability of the escapement being tripped. The key-lever is arrested at such a point that the type-bar will continue its movement toward the platen with sufficient force to make the impression for printing purposes, but without cutting or injuring the paper or the platen, thereby permitting accent type and the like 10 to be employed. The movement of the dead key-lever is such that it will not trip the escapement, thus the printing may be made to take effect either above or below the character previously printed by an ordinary key 15 which does not coöperate with a device or attachment 40. The device 40 is intended to be detachable from the comb plate so that it may be applied to coöperate with any one of the key-operated levers, and the stop 47 20 thereof may be adjusted by filing off the lower end or by bending the same. The body 45 of said device has a yielding or spring hooked portion 48 which is adapted to fit over the upper edge of the comb plate 43 and 25 at the lower edge of said body of the device 40 are hooks or lips 49 which are adapted to be passed about the lower edge of the comb plate 43 as shown best in Figs. 1, 9 and 11. The ribbon may be moved to and from the 30 printing point by any suitable mechanism. As shown, the vibrating mechanism is substantially the same as the construction of the mechanism shown in my Patent No. 1,121,044, dated December 15, 1914, except as 35 to one part. The exception referred to is in the lever 50 and the form or character of the slot 51 in said lever, the lever, except as to the slot, being substantially the same as in my Patent No. 1,121,043 dated December 15, 40 1914. This lever 50 has a body portion 52 which is pivoted, at 53, to an actuator or actuating member 54, and said lever has a bent over or overhanging portion 55 in which the angular slot 51 is formed. The lever 50 is 45 adjustable to various inclinations on its pivot 53 so as to present the slot 51 at different angles with respect to a roll 56 mounted on the lower end 57 of a ribbon vibrator 58. This vibrator 58 is pivoted, at 59, to a bracket 60 50 which is rigidly held to the carriage bed. The vibrator has an arm 61 extending substantially parallel to the platen 34^a and has its end 62 adapted to hold the ribbon and move the same to and from the printing 55 point, the said vibrator being in one or more parts as preferred. The lower end of the vibrator is provided with a second roll 63 which is adapted to enter a slot 64 formed in an arm 65 of the bracket 60 and which slot is 60 elongated and extends lengthwise of the platen. The actuator 54 is substantially L-shaped and is pivoted, at 66, to the bracket 60 and is normally forced in one direction by a spring 67, one end of which is held to a part 65 of the bracket 60 and the other end to a pro- jection 68 on the actuator or actuating member 54. The actuator 54 is provided with a slot 69 which is adapted to receive the bendable end 70 of an adjustable plate or bracket 71 which is mounted on the transverse bar 70 29 of the rocking frame 28 so that when the bar 28 is operated by the keys as already explained, it will move the actuator 54 inward against the tension of the spring 67, while on the release of the key the spring 67 will 75 return the actuator to its former and normal position. This actuator 54 is provided with an upwardly extending and integral portion 72. This part 72 is corrugated to provide several depressed parts and the said actuator 54 is slotted, at 73, through which passes the outer end of the lever 50. The lever 50 has a finger part 74 and has its body provided with an opening 75 through which may be seen a letter or character placed upon 80 the actuator 54. There are three of such characters S, B and R indicating three positions in which the lever 50 is adapted to be held. When in the position shown in the drawings, the vibrator is adapted to move 85 the black field of the ribbon to and from the printing point. If the lever 50 is moved so that the character R is seen through the opening 75, the red or other colored field of the ribbon will be moved to and from the 90 printing point, and if the lever 50 is moved so that the letter S appears under the opening 75, then the construction is such that the actuator 54 may be operated without giving more than a slight movement to the ribbon, 95 thus adapting the machine for making stencils. The substantially silent position of the lever 50 for stenciling places the slot 51 so that the side walls of the slot do not have much action, either cam or otherwise, on the 100 roll 56 and therefore the ribbon vibrator while it may have a slight upward movement, it is brought back and held below the printing point in substantially the manner shown and disclosed in my patents herein 105 referred to. In the lever 50 and the character of the slot 51 of said lever is the principal and substantially the only difference between the present construction of ribbon vibrating 110 mechanism and that disclosed in the said patents. The reason for the form of slot is that the actuating part of the lever 50 is in the part 76 of the slot 51 while the roll 56 may move in the angular or inactive part 115 77 of said slot without giving any further movement to the vibrator. That is, when an ordinary key is depressed, the tongue 19 thereof will engage the universal bar much sooner than the downwardly bent end 19^a of 120 the dead or silent key or keys 14, thus the universal bar and the rocking frame actuated thereby will move a greater distance 125 under the action of the ordinary key than under the action of the dead key. The an- 130

gular or inactive part 77 of the slot of the lever 50 is so arranged that when an ordinary key is depressed, the roll 56 of the ribbon vibrator will enter said angular part 77 of the slot without moving the vibrator, but will continue to move the rocking frame so as to trip the escapement, while the entire action of the dead key, owing to its tongue 19^a engaging the universal bar later, will 10 give a less movement to the universal bar and rocking frame as well as the ribbon actuator 54 so that said actuator would only be forced far enough for the roll 56 to be located at the angular portion of the slot 15 of the lever 50 as shown in dotted lines in Fig. 5. The ribbon is thus always lifted to the same height and the slot in the lever 50 is so formed that it forces the ribbon to its highest position when the ordinary key is 20 operated some time before the type reaches the platen, but when a dead or silent key is operated, the ribbon is made to cover the printing point just before the type reaches the platen. The stop 47, by forming a 25 bumper effect for the dead or silent key, prevents further action of said key on the universal bar and thus the rocking frame is prevented from moving far enough to trip the escapement.

30 From the foregoing, it will be evident that simple and efficient means is provided whereby any of the regular keys of a typewriter may be converted into a dead or silent key; that simple means is provided 35 whereby the ribbon vibrator may be operated to cover and uncover the printing point without tripping the escapement; that simple means is provided whereby the ribbon both when the regular keys are operated and when the dead keys are operated is moved to the same height; that a simple and efficient attachment is provided for giving a bumper effect to any one of the key-levers with which it co-operates; and that 40 said invention is simple in construction and may be applied to typewriting machines as ordinarily constructed with very little change.

Having thus described my invention, I 50 claim as new and desire to secure by Letters Patent:—

1. In a typewriting machine, the combination of a carriage, escapement mechanism for letter-spacing the carriage, universal bar mechanism adapted to trip the escapement, type, key-operated levers for moving the type and adapted to trip the escapement through the universal bar mechanism, an accent key-operated lever for imparting a 55 less movement to the universal bar mechanism and at a different part of its movement from the first-mentioned key-operated lever without tripping the escapement, and a stop 60 adapted for positive engagement by a part 65 of the accent key-operated lever to prevent

further movement thereof and at a point just prior to the printing by the type but in such a way as to permit the type by its momentum to make an impression.

2. In a typewriting machine, the combination of a carriage, escapement mechanism for letter-spacing the carriage, ribbon vibrating mechanism, universal bar mechanism carrying a part of the ribbon vibrating mechanism and adapted to operate said ribbon vibrating mechanism and trip the escapement, type, key-operated levers for moving the type and the universal bar mechanism and adapted to trip the escapement through said universal bar mechanism, an accent key-operated lever for imparting a less movement to the universal bar mechanism to operate the ribbon vibrating mechanism without tripping the escapement, and a stop adapted for positive engagement by a part of the accent key-operated lever to prevent further movement thereof and at a point just prior to the printing by the type but in such a way as to permit the type by its momentum to make an impression. 70 75 80 85 90

3. In a typewriting machine, the combination of a carriage, escapement mechanism for letter-spacing the carriage, universal bar mechanism adapted to trip the escapement, type, key-operated levers for moving the type and adapted to trip the escapement through the universal bar mechanism, an accent key-operated lever for imparting a less movement to the universal bar mechanism and at a different part of its movement from the first-mentioned key-operated levers, and a stop adapted for positive engagement by a part of the accent key-operated lever to prevent further movement thereof and at a point just prior to the printing by the type but in such a way as to permit the type by its momentum to make an impression. 95 100 105

4. In a typewriting machine, the combination of a carriage, key-operated levers, type operated by said levers, escapement mechanism for the carriage, a universal bar operatively connected to said escapement mechanism and normally separated from the key-operated levers, and stopping means for arresting a part only of said key-operated levers at such a point that sufficient movement to actuate the escapement mechanism will not be given said bar. 110 115

5. In a typewriting machine, the combination of a carriage, a key-operated lever, type operated by said lever, escapement mechanism for the carriage, a universal bar operatively connected to said escapement mechanism and normally separated from the key-operated lever, and a positive stop for arresting said lever at such a point that sufficient movement to actuate the escapement mechanism will not be given said bar. 120 125

6. In a typewriting machine, the combination of a carriage, ribbon vibratory mecha- 130

- anism, type, escapement mechanism, key-operated levers operatively connected to the type, a guide plate for the levers, means whereby the ribbon mechanism may be operated when the levers are depressed, and a device detachably held to the guide plate and adapted to make said lever ineffective to trip the escapement, said device having a body portion provided with a slot and with a stop adapted to be engaged by the key-operated lever and with a hooked portion adapted to fit over said plate and with lips adapted to engage the lower edge of said plate. 7. In a typewriting machine, the combination of a carriage, ribbon vibratory mechanism, type, key-operated levers operatively connected to the type, a guide plate for the levers, means whereby the ribbon mechanism may be operated when the key-levers are depressed, and a device adapted to be detachably held to the guide plate and having a body portion provided with a slot and with a stop adapted to be engaged by the key-operated lever. 8. In a typewriting machine, the combination of a carriage, ribbon vibratory mechanism, type, key-operated levers operatively connected to the type, a guide plate having guide slots for the levers, and a device arranged on the guide plate and having a body portion provided with a slot adapted to register with a slot in the guide plate and with a stop adapted to be engaged by one of the key-operated levers, said device being provided with means for detachably holding the device to said plate. 9. In a typewriting machine, the combination of a carriage, ribbon vibrating mechanism, escapement mechanism, a key-lever, means connecting the key-lever to operate the ribbon vibrating mechanism, a guide plate, and a device detachably held to said guide plate and adapted to form a stop for said key-lever. 10. In a typewriting machine, the combination of a carriage, ribbon vibrating mechanism, escapement mechanism, a key-lever, means connecting the key-lever to operate the ribbon vibrating mechanism, a guide plate, and a stop arranged on said guide plate adapted to be engaged by said lever. 11. In a typewriting machine, the combination of a carriage, ribbon vibrating mechanism adapted to move the ribbon to and from the printing point or permit it to remain inactive, a key-operated lever, means whereby the lever may operate the ribbon vibrating and the escapement mechanisms, an accent key-operated lever, a guide plate, and a device held to said guide plate to form a stop for said accent lever. 12. In a typewriting machine, the combination of a support, a carriage, escapement mechanism, ribbon vibrating mechanism, key-levers, type-bars operated by said key-levers, means whereby the key-levers may operate the ribbon vibrating mechanism and trip the escapement, a silent key operatively connected to a type-bar, a comb plate guiding said key, means for limiting the movement of said silent key, and a device having a slotted plate-like body and ends forming clips adapted to engage and be detachably held to the comb plate and forming a positive stop for the silent key. 13. In a typewriting machine, the combination of a support, a carriage, escapement mechanism, ribbon vibrating mechanism, key-operated levers, type-bars operated by said levers, means whereby the key-operated levers may operate the ribbon vibrating mechanism and trip the escapement, a silent key operatively connected to a type-bar, a comb plate guiding said key, and a device having a slotted plate-like body and ends forming clips adapted to engage and be detachably held to the comb plate and forming a positive stop for the silent key. 14. In a typewriting machine, the combination of a carriage, key-levers, type-bars operated by said key-levers, a silent key operatively connected to a type-bar, a comb plate guiding said key, and a device detachably held to the comb plate and forming a positive stop for the silent key. 15. In a typewriting machine, the combination of a carriage, a platen mounted in said carriage, escapement mechanism for said carriage, ribbon vibrating mechanism including an actuating lever having an active and an inactive portion, and key-operated levers for giving the lever different throws, the escapement mechanism being tripped only when the lever is given its greatest throw. 16. In a typewriting machine, the combination of a carriage, a platen mounted in said carriage, escapement mechanism for said carriage, ribbon vibrating mechanism including a vibrator actuating lever having an active and an inactive portion, key-operated levers for imparting movement to said vibrator actuating lever and tripping the escapement, an accent key-operated lever for operating the first-mentioned lever without tripping the escapement, and type operated by all of said key-operated levers. 17. In a typewriting machine, the combination of a support, a carriage, a platen mounted on said carriage, an actuator, a rocking frame operatively connected to said actuator, a key-lever adapted to operate said rocking frame, a pivotally held lever having an overhanging portion provided with an angular slot therein forming active and inactive parts, and a ribbon holder having a part thereof adapted to enter said slot and be given movement by the lever when the actuator is moved. 18. In a typewriting machine, the combination of a support, a carriage, a platen mounted on said carriage, an actuator, a rocking frame operatively connected to said actuator, a key-lever adapted to operate said rocking frame, a pivotally held lever having an overhanging portion provided with an angular slot therein forming active and inactive parts, and a ribbon holder having a part thereof adapted to enter said slot and be given movement by the lever when the actuator is moved.

nation of a support, a carriage, a platen mounted on said carriage, an actuator, a key-operated lever adapted to operate said actuator, a pivotally held lever having an overhanging portion provided with active and inactive parts, and a ribbon holder adapted to be given movement by the active part of the lever when the actuator is moved.

19. In a typewriting machine, the combination of a support, a carriage, a platen mounted on said carriage, an actuator, a

rocking frame operatively connected to said actuator, a key-lever adapted to operate said rocking frame, a pivotally held lever having an angular slot therein forming an active and inactive portion, and a ribbon holder having a part thereof adapted to enter said slot and be given movement by the lever when the actuator is moved.

This specification signed and witnessed 20 this 11th day of July A. D. 1914.

OTTO PETERMANN.
